UNITED STATES PATENT OFFICE

2,095,885

APPLICATION OF STUDS

Salvador Moreira and Ernest J. Sabol, Worcester, Mass., assignors to The American Steel and Wire Company of New Jersey, a corporation of New Jersey

Application May 3, 1935, Serial No. 19,745

2 Claims. (Cl. 29—169)

This invention is an improved method of fixing metal studs to metal bodies provided with holes in which the studs may be fitted and is particularly concerned with the application of 5 stud terminal rail bonds to railroad rails. One of the objects is to increase the holding power of such studs after they have been fixed to the bodies. Other objects may be inferred.

Referring to the accompanying drawing:

10 Figures 1, 2 and 3 are cross-sectional views of a stud terminal rail bond with its stud fitted in a hole in the head of a railroad rail, the respective views showing various phases of the new method.

15 Figures 4 and 5 are similar cross-sectional views showing various phases of a modified form of the new method.

Figures 6 and 7 are further similar views showing a further modification of the new method.

20 More particularly, Figure 1 shows a cross-sectional portion of the head of a rail 1 in which a hole 2 is formed. This hole must be relatively shallow so as not to materially weaken the rail. The terminal 3 has its stud 4 fitted in this hole, 25 the latter being of less depth than the length of this stud. Therefore, when a compressive force is applied to the outside of the terminal 3 in line with the stud 4 the latter will be expanded in the hole 2 due to the resulting longitudinal application of force to the same.

According to the new method the compressive force is not only applied longitudinally to the stud 4 so as to cause it to expand in the hole 2 but force is also applied to the rail head 1 adjacent the hole 2 so as to cause the metal of the rail to flow toward the stud and penetrate the same.

The above forces may be applied by any suitable tool, such as the concussive tool 5 having a 40 reduced striking end 6 which is illustrated by Figures 1 through 3. In this group of figures, Figure 2 illustrates the tool 5 as it appears while striking the terminal 3. It will be noted that the reduced end 6 is aimed so as to strike the end of 45 the terminal and thus cause expansion of the stud 4 in the hole 2. Furthermore, it penetrates the end of the terminal and a portion of the head of the rail 1 which is adjacent the hole 2. This causes the metal of the rail to flow into the stud 50 4, as at 7. Figure 3 shows the terminal after it has been thus fixed to the rail head 1. It will be noted that the stud 4 is not only expanded in the hole 2 but is locked in place by the metal of the rail which has penetrated the stud.

55 Figures 4 and 5 show the same terminal, but

show a tool 8 which has a striking end 9 providing a face that angles away from the end of the terminal 3 and a flat face 10 which can strike the end of the terminal in line with the stud 4.

When this tool 8 strikes in the manner indicated by Figure 4, its flat face 10 applies a compressive force longitudinally to the stud 4. Simultaneously, its striking end 9 penetrates the head 1 and, because of the angular face of this end 9, applies force to the head at a position adjacent the hole 2 and in a direction which angles toward the latter, so as to cause the metal of the rail to flow and penetrate into the stud 4. Figure 5 illustrates the result obtained by the use of this 15 secondly described tool, it being noted that here again the locking effect is obtained.

Figures 6 and 7 are further views of the terminal 3 with its stud 4 positioned in the hole 2 in the rail head 1. At this point it should be understood that stud terminal bonds are generally made of softer metal than is the metal of the railroad rail. Such is assumed to be so in the case of the elements illustrated by Figures 6 and 7.

In Figure 6 it may be assumed that the terminal 3 has been applied to the head 1 by pressure applied to the terminal so as to cause expansion of the stud 4. The next step, therefore, is to provide the locking action. For this a tool 11 is 20 used, which is in the nature of a bridge providing a striking end 12 having an angular face 13. When this tool is arranged as shown, it is struck a blow so as to apply sufficient compression to the relatively harder metal of the rail head at a 25 position adjacent the hole 2 which causes this relatively harder metal to flow, whereby the metal tends to flow into the relatively softer metal of the stud. Figure 7 illustrates the final result obtained, the displaced metal of the rail again 30 providing the desired locking.

Throughout the foregoing it is to be understood that various applications of pressure described may result either from a concussive force or from the slow application of a force such as is obtained by a press. Furthermore, in all cases the force used should be sufficient to cause the metal of the rail to flow as has been described.

We claim:

1. A method of fixing a rail bond terminal stud 55 in a recess formed in a railroad rail when said stud is longer than said recess is deep, including forcing said stud longitudinally against the end of said recess so as to expand said stud and applying force to the surface of said rail adjacent 55

said recess so as to force the rail metal to flow towards said stud and to penetrate the latter.

2. A method of fixing a rail bond terminal stud in a recess formed in a railroad rail when said stud is longer than said recess is deep, including forcing said stud longitudinally against the end of said recess so as to expand said stud and

simultaneously applying force to the surface of said rail adjacent said recess so as to force the rail metal to flow towards said stud and to penetrate the latter, whereby to lock said stud against any tendency to leave said recess.

SALVADOR MOREIRA.
ERNEST J. SABOL.
